[57] CLAIM

The ornamental design for a trash cart, substantially as shown and described.

DESCRIPTION

FIG. 1 is a front perspective view of a "trash cart" showing our new design;

FIG. 2 is a right side elevational view thereof;

FIG. 3 is a front elevational view thereof;

FIG. 4 is a rear elevational view thereof, and

FIG. 5 is a bottom plan view thereof.

The left side, not shown, is a mirror image of the right side shown in FIG. 2.
